UNITED STATES PATENT OFFICE.

WALTER J. BARRON, OF NEW YORK, N. Y., AND HENRY W. MERRITT, OF SPRINGFIELD, MASSACHUSETTS, ASSIGNORS TO DENSMORE TYPEWRITER COMPANY, OF SYRACUSE, NEW YORK, A CORPORATION OF NEW YORK.

TYPE-WRITING MACHINE.

No. 873,487.

Specification of Letters Patent.

Patented Dec. 10, 1907.

Original application filed February 6, 1902, Serial No. 92,839. Divided and this application filed June 3, 1902, Serial No. 110,042.

To all whom it may concern:

Be it known that we, WALTER J. BARRON and HENRY W. MERRITT, citizens of the United States, and residents, respectively, of 5 borough of Brooklyn, county of Kings, city of New York, and State of New York, and of Springfield, county of Hampden, and State of Massachusetts, have invented certain new and useful Improvements in Type-Writing 10 Machines, of which the following is a specification.

Our invention relates to platen shifting mechanism for typewriting machines, the object of the invention being to provide simple and efficient mechanism of the character specified which may be actuated by any one of a plurality of shift keys when the platen is in either the upper or lower case position.

To these and other ends which will appear 15 in the following description our invention consists in the novel construction of features, arrangements of elements and combinations of parts to be hereinafter described and claimed.

20 In the accompanying drawings wherein like reference characters designate corresponding parts in the different views, and wherein parts have been omitted or broken away, Figure 1 is a front to rear vertical sectional view of one form of typewriting machine embodying our invention. Fig. 2 is a fragmentary plan view of the same.

The present application is a division of our 25 application Serial No. 92,839, filed Feb. 6, 1902, and while the invention is shown applied to a Densmore typewriting machine, it should be understood that it may be employed in other characters of typewriting machines.

30 1 designates the main frame of the machine, 2 the usual top plate and 3 the key levers which are connected by links 4, in a suitable manner, to actuate the type bars 5, which are pivoted to hangers 6 secured to the 35 top plate 2. Each of the key levers 3 is provided with the usual figure key 7 and with a hook 8 which bears upon a transverse universal bar 9, that has a rearwardly extending arm at each end which is pivoted to the 40 frame of the machine at 10.

Pivoted to the universal bar 9, at 11, is a link 12 preferably made of two parts, which may be adjustably united by screw threaded connections 13. The upper end of this link

12 is provided with an eye 14 that engages a notched portion 15 of an arm 16, which is preferably in the form of a screw, that extends through a threaded hole in a depending stud 17 of the dog rocker, whereby the said arm may be adjusted to bring the inner end thereof closer to or to move it further from the pivotal center of the rocker, in order to vary or regulate the throw imparted to the rocker and the feed dogs carried thereby. The adjustment 13 enables the link 12 to be lengthened or shortened in accordance with the adjustment of the arm 16. The feed dogs 18 18^x and their rocker 19 after actuation are returned to normal position by a spring 20, which is suitably connected at one end to an arm 20^x on the rocker and at its other end to a fixed arm 21 on the machine frame. The feed dogs 18 and 18^x coöperate with a feed wheel 22, which is secured to a sleeve 23 that surrounds and is loosely carried upon a shaft 24, and is prevented from moving longitudinally thereon in one direction by a sleeve 23^a which is secured to the shaft 24 by a set screw. The shaft 24 has cone bearings at its ends which coöperate with anti-friction balls 24^a which revolve in circular race-ways. One raceway is formed in a bracket 24^b that is secured to the top plate 2 of the machine, and the other raceway is formed in a screw-threaded adjustable plug 24^c that takes into a threaded opening in the bracket arm 24^d which forms part of the bracket 24^b. By these means an efficient ball bearing support is provided for the shaft 24 and the plug 24^c may be turned by a screw driver, (a slot being provided in the plug for this purpose) to compensate for any wear that may take place in the balls or the bearings.

An operative connection is maintained between the feed wheel 22 and the shaft 24 which has a feed pinion 25 secured to the forward end thereof and this pinion meshes with a feed rack 26.

From the foregoing description it will be understood that a movement of the feed dogs will permit the feed wheel to rotate and thus permit the carriage to be moved by the usual carriage spring (not shown).

The feed rack 26 is mounted upon arms 27 that project from a rock shaft 28 to which is secured a leaf spring 29, the free end of which bears against a portion of the carriage as

shown at 30 in order to maintain the feed rack 26 normally in engagement with its co-operating feed pinion 25. The rock shaft 28 is likewise provided with a lug 31 which is bifurcated at 32 so as to provide stops 33 that co-operate with a fixed pin 34 carried by the carriage in order to limit the oscillation of the rock shaft. The rock shaft 29 likewise has a finger piece or arm 35 secured to one end thereof, preferably at the left hand end, so that a depression of this finger piece or arm will rock the shaft 28, thus disengaging the feed rack 26 from its pinion 25 to permit the carriage to be freely moved in either direction.

In the ordinary Densmore machine the paper carriage as an entirety comprises three distinct members, viz., a frame carrying the platen, a carriage in which the platen frame is mounted or supported and a truck or frame that carries the feed rack. The truck comprises a frame 36, in which the rock shaft 28 that extends substantially from end to end of the frame, is pivoted. The rear portion of the truck 36 is grooved longitudinally at 37 to form a track for co-operation with horizontally disposed bearing rollers 38 carried by the rear guide rail 39. The guide rail 39 is secured to the top plate 2 of the machine by angular brackets 40 and one end of each of the brackets is secured to the top-plate 2 by headed screws 41, which pass through slots and enter tapped holes in the top-plate.

Projecting forwardly from the truck 36 are eyes 42 that surround a tubular bearing sleeve 43 and which may be secured thereto by screws 44. The sleeve 43 may be of any desired length and surrounds a traverse rod 45 which is supported upon arms 46 projecting up from the top-plate and the rod is provided with two parallel longitudinal grooves 47 which receive two sets of anti-friction rollers 48-49.

In order to prevent the carriage from lifting, we provide the sleeve 43 with pins 50 which normally are out of contact with the underside of the traverse rod.

The platen carriage comprises a four-sided frame made up of end-plates 51, the rear bar 52 and front connecting bars 53-54.

Secured to the rear bar 52 are forks 55 and a bearing arm 56 that co-operate with the sleeve 43 and with projections 36^x that are carried by the truck, to effect a longitudinal movement of the platen carriage with the truck and to permit a transverse movement of the platen frame for upper and lower case printing as will hereinafter appear and also to permit the platen carriage and frame to be swung back around the sleeve 43 when desired.

The end plates 51 of the platen carriage may be provided with slotted bearings 57 for the reception of a shaft 58 of the platen

59 and may likewise be provided with bearing surfaces 60 for anti-friction rollers 61 that are carried by the platen frame in substantially the same manner as in the well-known Densmore machine.

The bar 54, in addition to forming a connecting bar between the end plates of the platen carriage, may be grooved as indicated at 62 to form a track-way for anti-friction rollers 63 that are carried by a shift bar 64 and this shift bar is provided with depending arms 65 which are pivoted to the framing of the machine. There are two of these depending arms, and a rock shaft 66 extends from side to side of the machine and serves as pivots for the arms. The depending arm 65 at one side of the machine, preferably at the left hand side, is extended to form a depending projection or arm 67 which is slotted or apertured at 68. Pivoted to the lower end of this arm and on the inner side thereof at 69 is a vibratory link 70 which has a transverse slot 71 formed on an arc struck from the pivot 69 and a slot 72 in the link radiates from the pivot 69. The upper end of this link is pivotally connected at 73 to a two-part adjustable connecting rod 74, the lower end of said rod being pivoted to a shift key lever 75 at 76. This shift key lever 75 is provided with the usual key 77, and is rigidly connected to an arm 78 extending from a rock shaft 79, which is mounted in suitable bearings in the framing of the machine and extends from side to side thereof. The right hand end of the rock shaft 79 is connected in a similar manner to a shift key lever 80 having a key head 81.

Pivoted at 82 on the outer side of the arm 67 is a three-arm lever 83, one arm of which constitutes or forms a finger piece 84 by which the lever may be shifted by hand; the second arm 85 is pivotally connected at 86 to an extension of a coiled contractile spring 87 which is connected at its lower end to a fixed adjusting bar 88, the lower face of which is provided with serrations 89 to engage the lower hooked end of the spring and retain it in the position to which it is adjusted along the bar 88. The third arm of the lever 83 carries a pin 90 that projects through the opening or slot 68 in the depending arm 67 and into the radial opening 72 in the link 70. It will be observed that the slot 68 conforms substantially to an arc struck from the pivot 82 as a center. Beyond both sides of the depending arm 67, in which it is fixed, the left hand projecting end of said pivot is provided with the third arm of the lever 83, while the right hand extension of said pivot enters the slot 71 in the link 70 and limits a vibratory movement thereof. This portion of the pivot is headed, as shown in Fig. 1, so as to overlie the edges of the slot 71 and serve as a guide for the link 70 in its swinging movements about the pivot 69.

It will be seen that the tension of the spring 87 is exerted to maintain the shift bar and platen carriage to the rear, when the parts are in the positions represented in Fig. 1. It will likewise be observed that when the parts are in the positions represented in this figure, a depression of either one of the shift keys 77 or 81 will be effective to move the shift bar and platen in the direction of the arrow in Fig. 1. When, however, the finger piece 84 is depressed, the lever moves around its pivot 82 and the upper end of the spring is shifted from the position shown in Fig. 1 to the opposite or forward side of the pivot or shaft 66 and the upper end of the link 70 is moved to the opposite or rear side of the pivot or shaft 66 by reason of the pin and slot connection 90—72, between the lever 83 and the link 70. The respective points of connection of the upper ends of the spring and the rod 74 are always on opposite sides of the pivot or shaft 66 of the shifter bar, and when the point of connection of the spring is in the rear of said pivot or shaft 66, the spring operates to maintain the carriage and platen in their rearward positions and to restore them thereto after they have been shifted forwardly by a depression of either of the shift keys 77 or 81, the depression of either of said keys causing a downward pull on the connecting rod 74 which, acting on the stud 73 and the link 70, effects a slight rocking of the arm 67 on the pivot 66 and a forward movement of the shifter bar and platen carriage when the parts are in the position shown in Fig. 1. When, however, the finger piece 84 is depressed, the lever, of which it forms a part and which carries the upper end of the spring, is swung forwardly while the link which is connected to said lever and which carries the rod 74 is swung rearwardly so that in the changed position of the parts the spring will then act to maintain the carriage and the platen in their forward positions and to restore them thereto after either of the shift keys 77 or 81 has been depressed and then released. In the position of the parts at Fig. 1, the platen may be said to be in condition to receive the impressions of the lower case types but when moved forwardly, by depressing either shift key, the platen will be in proper position to take type impressions from the upper case types. When the finger key 84 has been pushed down, as before explained, the platen will then be held normally in upper case position, or for the printing of all capitals, but when it may be desired to imprint the lower case characters, the platen may be shifted rearwardly temporarily by depressing either one of the shift keys, and then, after printing such types, the platen will be restored again to the normal or upper case position by relieving the shift key from pressure.

When the parts are shifted from the posi-

tion represented in Fig. 1, the shift keys 77 and 81 will be maintained in the same positions that they were in before the shifting was effected and both of said keys are operable at all times to temporarily shift the platen from one case position to another.

The finger piece 84 and its immediate connecting device constitute what we term a permanent shifting mechanism, because the movement thereof will cause the shift bar to move the platen to either the upper or lower case printing position and with the aid of the spring 87 retain it in such position. The shift keys 77 and 81 we term temporary shift keys because they are operable to move the platen from the position to which it has been shifted or moved by the permanent shift key mechanism, but the platen will be restored to its initial position, determined by the permanent shift key, as soon as pressure is released from the so-called temporary shift keys 77 or 81. This shifting mechanism is of especial advantage in that it provides means for shifting the platen frame to the lower or upper case printing position and likewise provides a temporary shift key at each side of the key board, which keys are at all times operable to move the platen from the position to which it has been moved by the permanent shift key and permit the platen to be restored to such position as soon as pressure upon either of the temporary shift keys is released.

Certain of the features shown and described are not claimed herein but constitute the subject-matter of other pending applications.

What we claim as new and desire to secure by Letters Patent, is:—

1. In a typewriting machine, the combination of a paper carriage, a transversely movable platen, key operated means for moving the platen transversely to any one of a plurality of positions and for retaining it in the position to which it has been moved, temporary shift keys one at each side of the key board, a rigid connection between said temporary shift keys, operative connections between one of said temporary shift keys and the key operated mechanism whereby both shift keys are operable to move the platen transversely from the position to which it has been moved by the first mentioned key operated mechanism and for permitting said platen to be restored to its initial position when pressure is removed from either of the temporary shift keys, both of the said temporary shift keys being at all times operable irrespective of the position of the key operated means.

2. In a platen shifting device for typewriting machines, the combination of a shift rod, a pivoted depending arm connected to said shift rod, a spring, an arm which is pivoted to the depending arm of the shift rod

130

125

110

115

120

and is connected to one end of the spring, hand operated means for moving the pivoted arm to shift the tension of the spring to either side of the center on which the shift 5 rod swings to apply the force of the spring in either one of two directions and thus move the shift rod accordingly, a rod as 74 controlled by said hand operated means and adapted at all times to act in opposition to 10 said spring, and a plurality of finger keys which are at all times operable to actuate the rod 74 and to enable it to be automatically restored when pressure on the actuated finger key is released.

15 3. In a typewriting machine, the combination of a shiftable member, means for holding said shiftable member in either lower or upper case position at will, a transverse rock shaft connected to said shiftable member, 20 and two temporary shift keys one on each side of the keyboard and both connected to

said rock shaft on the same side of its axis, whereby both said temporary shift keys are adapted to shift the shiftable member in the same direction from normal position,—that 25 is to say, from lower case to upper case position or from upper case to lower case position according as the shiftable member is permanently held in one or the other of the two case positions and to afford an automatic return movement of the shiftable member when pressure on the actuated temporary shift key is released.

Signed at the borough of Manhattan, city of New York, in the county of New York, 35 and State of New York, this second day of June, A. D. 1902.
